UNITED STATES PATENT OFFICE.

JOSEPH W. PUTNAM, OF GRAND RAPIDS, MICHIGAN.

FOLDING BOX.

940,941.

Specification of Letters Patent. Patented Nov. 23, 1909.

Application filed April 12, 1909. Serial No. 489,251.

To all whom it may concern:

Be it known that I, JOSEPH W. PUTNAM, a citizen of the United States of America, residing at Grand Rapids, in the county of 5 Kent and State of Michigan, have invented certain new and useful Improvements in Folding Boxes; and I do hereby declare the following to be a full, clear, and exact description of the invention, such as will 10 enable others skilled in the art to which it appertains to make and use the same.

My invention relates to improvements in folding boxes; and its object is to provide a box that can be very quickly opened and 15 adjusted for use; to provide improved means for holding the cover or closure in place, and to provide the device with various new and useful features, hereinafter more fully described and particularly pointed out in 20 the claims, reference being had to the accompanying drawings, in which:

Figure 1 is a perspective of a device embodying my invention adjusted for use; Fig. 2 a detail of one end of the same partially folded for storage or otherwise; Fig. 3 is a detail in vertical section of a portion of the box and cover attached thereto; and, Fig. 4 a detail in plan view of one end of the box adjusted as in Fig. 1.

Like numbers refer to like parts in all of the figures.

1 represents the bottom, 2 the sides, and 3 the ends of a folding box. The sides and ends at the respective corners are connected by integral folding triangular members 5 and 6, each consisting of equal right-angled triangles which together form, when spread out flat, a rectangular or square portion, each side of which is equal to the width of 40 the side and end portions. The triangular portion, adjacent to the end 3, is folded upon the same and secured thereto by any convenient fastening means, preferably a staple fastener 8. This fastener being applied by 45 first inserting the same through both triangles and the end, the outer triangle 5 first having a circular portion 7 nearly or quite severed from the same, whereby the said severed portion serves as a washer for the 50 fastener, and the triangle 5 is released.

When folded and out of use, the ends 3 are first turned inward and the two triangles at each corner opened out in the same plane between the ends and the sides as illustrated

in Fig. 2. The structure thus folds down 55 substantially flat and thin for storage or transportation.

To strengthen the upper edges of the sides, which are usually longer than the ends and to also serve as locking members, the 60 sides are extended as at 4 and folded inward and downward upon the inside of the sides and secured by any convenient means, preferably staples 9 located at a sufficient distance from the ends to permit the free 65 corners of the extensions to spring slightly inward. This folded portion serves as a locking member by engaging the inner surface of the ends 3 which are held in vertical position thereby when the device is opened 70 up. The cover or closure of the box is made in the same way and enough larger to go freely outside of the box proper, and is detachably secured in place thereon by fasteners preferably made of thin strips of 75 metal folded to form outwardly projecting downwardly inclined hooks 10 which engage the inner edge of the folded members 4, as illustrated in Fig. 3, and thus hold the cover or closure securely in place. This strip 80 forming the hook 10, is also folded and extended upward as at 11, and thus holds the hook in position, and the respective ends of the strip are inserted through the side of the box and oppositely clenched upon the 85 inner surface of the same as at 12, thus securely holding the hook in place and inclined outward as illustrated. The closure is readily released by manually springing the lower edges of the same outward until 90 free from the hooks.

Particular attention is called to the manner in which this device is opened up for use by a practically automatic movement. Heretofore in folding boxes one objection 95 thereto is the time required to adjust the box for use, which usually requires that the fastening devices shall each be manually adjusted, usually at each one of the four corners of the box. In the construction shown, 100 all that is required is to engage the fingers with the upper edges of the respective end members 3 and simultaneously pull them upward and outward in opposite directions to the vertical position. They will thus 105 readily pass the ends of the folded members 4 and be simultaneously engaged thereby at all four corners without any further or spe-

cial manipulation. The box is thus instantaneously adjusted for use, which is of great advantage in this class of goods.

What I claim is:—

- 5 1. A folding box, comprising a side and end adapted to fold inward and to turn from horizontal to vertical position, a square integral connecting portion between the same foldable into two superposed right-angled triangles upon the outside of the end, the outer triangle having a portion severed therefrom to form a washer, and a staple extending through the washer, the inner triangle and the end and securing the same to each other.
- 10 2. A folding box, comprising a bottom, sides and ends foldable inward upon the bottom and adapted to turn to a position at right angles to the same, extensions upon the upper edges of the sides folded inward and secured with their free corners adapted to spring inward and engage the ends to automatically lock the same in vertical position, and means foldable upon the outside of the ends for adjustably connecting the ends and sides at their adjacent ends and supporting the ends against outward movement.
- 15 3. A folding box, comprising a bottom, integral sides and ends foldable inward upon the bottom and adapted to turn outward to a vertical position, a square integral portion at each corner folded into two right-angled triangles upon the outside of the box, one of said triangles being secured to the end of the box and supporting the same against outward movement when in vertical position, and extensions on the upper edges of the sides folded inward and adapted to engage the inner surface of the ends and hold them in vertical position.
- 20 4. A folding box, comprising a bottom, sides and ends adapted to fold inward upon the same and to turn upward to a vertical

position, connecting corner portions between the sides and ends foldable into two superposed right-angled triangles upon the outside of the ends and supporting the same against outward movement, means for permanently securing the inner triangles to the ends, extensions on the upper edges of the sides and folded inward upon the same and also secured thereto and adapted at their ends to automatically engage the inner sides of the ends and hold the same in vertical position.

5. A folding box, comprising a bottom, ends and sides adapted to fold inward upon the same and also to turn to a vertical position, square connecting portions between the ends and sides at the respective corners of the box, said portions being foldable into two superposed right-angled triangles upon the outside of the ends, a portion of the outer triangle being severed therefrom, fastenings extending through said severed portion and the inner triangle and securing the same to the end, and extensions to the upper edges of the sides folded inward upon the same and adapted to engage and hold the ends in vertical position.

6. A folding box, comprising a box, a closure for the same having inwardly projecting shoulders, a strip of sheet metal folded upon itself to form a hook member thence extended oppositely from the hook member upon the surface of a box and thence folded upon itself and having its ends extending through the side of the box and clenched upon the inner surface thereof.

In testimony whereof I affix my signature in presence of two witnesses.

JOSEPH W. PUTNAM.
